(57) CLAIM

The ornamental design for a typeface as shown and described.

DESCRIPTION

FIGS. 1-4 illustrate a typeface showing our new design, including primary and alternate characters and symbols, in a regular format;

FIGS. 5-8 illustrate the typeface showing our new design, including primary and alternate characters and symbols, in an italic format;

FIGS. 9-12 illustrate the typeface showing our new design, including primary and alternate characters and symbols, in a bold format;

FIGS. 13-16 illustrate the typeface showing our new design, including primary and alternate characters and symbols, in a bold italic format;

FIGS. 17-20 illustrate the typeface showing our new design, including primary and alternate characters and symbols, in a condensed regular format;

FIGS. 21-24 illustrate the typeface showing our new design, including primary and alternate characters and symbols, in a condensed bold format;

FIGS. 25-28 illustrate the typeface showing our new design, including primary and alternate characters and symbols, in a wide format; and,

FIGS. 29-32 illustrate the typeface showing our new design, including primary and alternate characters and symbols, in a wide bold format.

The exemplary alphabet sentences shown in FIGS. 4, 8, 12, 16, 20, 24, 28, and 32, illustrate the claimed typeface in use. The words and phrases shown form no part of the claimed design.
